(57) **CLAIM**

The ornamental design for a removable modular desk attachment, as shown and described.

DESCRIPTION

FIG. 1 is a bottom perspective view of a removable modular desk attachment, showing our new design.

FIG. 2 is a front view thereof.

FIG. 3 is a back view thereof.

FIG. 4 is a left side view thereof.

FIG. 5 is a right side view thereof.

FIG. 6 is a bottom view thereof; and,

FIG. 7 is a top view, according to an embodiment of the invention.

In the drawings, the broken lines adjacent to the shaded surfaces represent the boundaries of the claimed portion of the design and form no part thereof. All other broken lines show portions of the removable modular desk attachment that form no part of the claimed design.
